UNITED STATES PATENT OFFICE.

RALPH GIARDINA, OF ALGIERS, LOUISIANA; JOSEPH (GIUSEPPE) GIARDINO ADMINISTRATOR OF THE SUCCESSION OF RAFAELLE GIARDINO, ALSO CALLED RALPH GIARDINA.

BOMB.

1,323,221.

Specification of Letters Patent. Patented Nov. 25, 1919.

Application filed June 1, 1916. Serial No. 101,067.

To all whom it may concern:

Be it known that I, RALPH GIARDINA, a subject of the King of Italy, residing at Algiers, in the parish of Orleans and State of Louisiana, have invented certain new and useful Improvements in Bombs, of which the following is a specification.

My present invention relates to improvements in bombs or other explosive missiles and projectiles, either of the type adapted to be projected from a gun or dropped from above, as from an aeroplane or other aerial craft, as an aid to military and similar operations.

The primary objects of the invention are to provide a bomb or other device of this character which will possess highly destructive abilities, it containing a great number of projectiles having powder charges which are preferably individual to the projectiles, means being provided for causing a distribution of the projectiles through a large range or zone when projected by said powder or explosive charges; and to provide novel and efficient means for causing discharge of the projectiles at the proper moment, the bomb or device being so constructed that, upon reaching the ground, the bomb will be lifted therefrom, whereupon the projectiles are discharged, distribution of the projectiles at the most effective height being thereby attained.

To these and other ends, the invention consists in certain improvements, and combinations and arrangements of parts, all as will be hereinafter more fully described, the novel features being pointed out particularly in the claims at the end of the specification.

In the accompanying drawing:—

Figure 1 represents a diametrical section taken vertically through a bomb constructed in accordance with the present invention.

Fig. 2 represents a horizontal section through the bomb on an enlarged scale and on the line 2—2 of Fig. 1.

Fig. 3 is a detail view showing a portion of the fuse which times the explosion of the bomb, and

Fig. 4 is a detail view showing one of the rows of chambers for the projectiles and their explosive charges.

Similar parts are designated by the same reference characters in the several views.

The bomb in its preferred form is shown in the accompanying drawing and will be

hereinafter described in detail. It is to be understood, however, that the invention is not restricted to the precise construction shown, as equivalent constructions are contemplated and modifications may be made in the construction of the bomb, all of which will be included within the scope of the claims.

In the present instance, the bomb comprises a body 1 which may be of any suitable shape or form. As shown, this body is spherical, thus enabling the bomb to be projected from a gun or dropped from aerial craft. The body is provided with an inner chamber 2 which is preferably located above the geometrical center of the bomb, thus lightening the weight of the bomb above its geometrical center, leaving a mass of metal at the bottom which operates by gravity to maintain the bomb in an upright position. Sets of projectile chambers 3 radiate from the axis of the chamber 2. These chambers are preferably arranged in rows, the chambers of each row being parallel or in alignment while the different rows of chambers radiate from the axis of the chamber 2. Each chamber is adapted to contain a projectile 4, and suitable provision is made for causing the discharge of the projectiles from their chambers. Preferably, and as shown, each chamber 3 contains a powder or explosive charge 5 for causing the discharge of the corresponding projectile from its respective chamber, a percussion cap 6 being provided at the rear of each chamber for igniting the powder charge therein. A suitable number of firing pin members 7 is provided, the number of these members corresponding, preferably, to the number of rows of projectile chambers. Each firing pin member 7 is provided with firing pins 8, the number of which corresponds to the number of projectile chambers 3 in each row. These firing pins are operative in bores 9 formed in the wall 10 which incloses the chamber 2, the firing pin members 7 being normally retracted or in the position shown in Fig. 1, and when moved outwardly, by means to be hereinafter described, the firing pins operate upon the percussion caps 6 of the projectile chambers of the respective row, thereby igniting the charges in these chambers and causing the projectiles therein to be discharged from such chambers. The wall 10 through which the firing pins operate may,

as shown, be formed of a cylinder set into the body of the bomb.

The means for actuating the firing pin members 7 comprises, in the present instance, a pair of heads 11 and 12, the head 11 being connected to the upper portions of the firing pin members 7 by radial links 13 which are pivoted to the head 11 at 14 and are pivotally connected at 15 to lugs 16 on the upper portions of the firing pin members, and the head 12 is operatively connected to the lower portions of the firing pin members by radial links 17, which links are pivoted to the head 12 at 18 and are operatively connected at 19 to lugs 20 formed on the lower portions of the firing pin members. Normally, the links 13 and 17 are inclined downwardly toward the heads 11 and 12, the firing pin members 7 being then in their retracted or inner positions. When, however, the heads 11 and 12 are elevated, the links 13 and 17 are brought toward horizontal positions, they then acting as toggles to force the firing pin members outwardly, thus causing the firing pins to explode the percussion caps and ignite the powder charges for the projectiles. The heads 11 and 12 are connected to move in unison, they being connected in the present instance by a sleeve 21 the lower end of which fits over a boss 22 on the upper side of the head 12, while the upper end of the sleeve has a flanged head 23 which is threaded internally upon a rod or stem 24 which passes axially through the sleeve. Screws or rivets 25 also secure the upper head 11 to the flanged head 23 of the sleeve.

Upward movement of the heads 11 and 12 to cause discharge of the projectiles from their chambers is effected, preferably, by the discharge of a powder charge or explosive at the proper moment. As shown, the lower or base portion of the body of the projectile is formed with a powder chamber 26 and the top of this powder chamber is normally closed by a plug 27, this plug having a flange or enlarged head 28 which bears on the under side of the lower head 12. The plug 27, as stated, normally closes the top of the powder chamber 26, but upon ignition of the powder in this chamber, the plug is forced upwardly, the plug in turn forcing upwardly the heads 11 and 12 and causing discharge of the projectiles in the manner hereinbefore stated. To accomplish this result, the plug 27 may, for example, have a few shallow threads 30 to engage similar threads in the top wall of the powder chamber 26, these threads serving to retain the plug normally in position, closing the top of the powder chamber, but the threads being stripped under the expansive force of the explosion in the chamber 26 when the powder in this chamber is ignited. Ignition of the powder in the chamber 26 is effected

through the burning of powder or a fuse in a bore 31 which leads into the bottom of the powder chamber 26 through a second and preferably larger powder chamber 32. This second powder chamber 32 is formed in the bottom or base of the bomb, it opening at the bottom of the bomb but being normally closed by a plug 33. The plug 33 will normally close the bottom of the powder chamber 32, but upon ignition of the powder in this chamber 32, the plug 33 will be forced downwardly out of the chamber 32, and the resulting pressure of the exploded gases will lift the bomb to an appropriate height above the ground. As shown, the plug 33 is normally retained in the bottom of the powder chamber 32 by a few shallow threads 34, these threads having sufficient strength to normally retain the plug in position but stripping and permitting discharge of the plug under the influence of an explosion of powder in the chamber 32.

The present invention also provides means for timing the explosion of the bomb. It comprises, preferably, a fuse 35 which is ignited upon the discharge of the bomb from a gun or upon dropping the bomb. The fuse in the present instance is contained in the top of the bomb, this top being formed preferably as a cap or lid 35 which fits upon the top of the body portion of the bomb and is secured thereto by screws or equivalent devices 36. The outer surface of the cap or lid 35 conforms to the general spherical form of the bomb. This cap or lid closes the interior chamber 2 and it is formed with a fuse chamber 37. In this chamber is placed a plate or diaphragm 38 having a spiral rib 39 on its upper side forming a spiral fuse channel 40, and another plate or diaphragm 41 is placed in the fuse chamber 37 beneath the plate 38 and this plate 41 is formed on its upper side with a spiral flange 42 forming a spiral fuse channel 43, while a spiral flange 44 is formed on the under side of the plate 41 and provides a spiral fuse channel 45. The cap is provided with a bore 46 which leads from the exterior of the bomb into the center of the fuse channel 40, the plate 38 is formed near its periphery with an aperture 47, the plate 41 is formed at its center with an aperture 48, and the flange 44 on the plate is formed with an aperture 49. A fuse passage 50 extends from the aperture 49 into the lower powder chamber 32. The plates having the flanges thereon which provide the spiral fuse channels are retained in the cap or lid by a cover plate 51 which may be threaded or otherwise retained in position. The under side of the cover plate 51 may also be provided with a guide 52 to coöperate with and steady the upper end of the rod or stem 24.

In loading the bomb, the various projec-

tile chambers 3 are provided with percus-
sion caps, they are provided with powder
charges, and projectiles are introduced into
these chambers, the firing pin members 7
5 being at this time retracted and retained
normally in retracted position by the plug
27 which is held by its threads in the top
of the powder chamber 26, the heads 11 and
12 which actuate the firing pin members
10 being held in their lower positions by the
rod or stem 24 which is attached to the plug
27 and to the sleeve 21 connecting the heads.
The fuse is placed in position, it extending
15 from the exterior through the bore 46 to the
center of the plate 38, it then winding in
convolutions outwardly from the center
toward the periphery of the plate 38
through the spiral fuse channel 40 until it
reaches the aperture 47, whereupon the fuse
20 enters the spiral fuse channel 43 and winds
inwardly to the center of the plate 41, it
then passing through the central aperture
48 in this plate and then winding outwardly
through the spiral fuse channel 45 until it
25 reaches the aperture 49 at the periphery of
the plate 41. The fuse then extends from
the aperture 49 through the fuse passage 50
and into the powder chamber 32. This
30 powder chamber and also the powder cham-
ber 26 are supplied with charges of powder,
the bore 31 connecting these chambers be-
ing provided with a fuse or containing
powder to act as a fuse to cause ignition of
35 powder in the chamber 26 after the powder
in the chamber 32 has been exploded.

When the bomb is discharged either from
a gun or from dropping it, it will land in
an upright position, due to the preponder-
ance of weight or mass at the bottom or
40 lower side of the bomb. The fuse is propor-
tioned to cause explosion of the bomb at the
proper moment or when the same has
reached a predetermined distance after dis-
charge. With the bomb resting in an up-
45 right position and on the plug 33, ignition
of the powder charge in the chamber 32 by
the fuse will cause the plug 33 to be blown
out of the bottom of this chamber, and the
resulting pressure of the exploded gases will
50 lift the bomb to a suitable height above the
ground. Ignition of the powder charge in
the chamber 32 is followed by explosion
of the powder charge in the chamber 26,
the explosion of the charge in the latter
55 chamber being timed to occur after the
bomb has been lifted to an appropriate
height above the ground by explosion of the

charge in the chamber 32. When the ex-
plosion occurs in the chamber 26, the plug
27 is drawn from the top thereof in an up-
ward direction, forcing the heads 11 and 12
upwardly with a quick motion whereby the
firing pin members 7 are all simultaneously
forced outwardly. This results in ignition
60 of the powder charges in the projectile
chambers and discharge of the projectiles
from these chambers in directions radiating
65 from the axis of the bomb or cylindrical
chamber 2.

By arranging the projectile chambers in 70
rows radiating in all directions from the
vertical axis of the bomb, a thorough dis-
tribution of the projectiles within the zone
of explosion of the bomb is accomplished.
Furthermore, by providing means for ele-
75 vating the bomb to an effective distance
above the ground, preparatory to the dis-
charge of the projectiles, the greatest ef-
fectiveness of the projectiles is attained.

I claim as my invention:— 80

1. A bomb comprising a plurality of rows
of projectile-containing chambers, said rows
of chambers being arranged in planes radi-
ating from a given axis, explosive charges
for said chambers, a member for each row 85
of chambers, each member carrying firing
pins for exploding the charges in the cham-
bers of the respective row, and means for
actuating the firing pin members embodying
heads connected to said members, an explo-
90 sive chamber, and means operative by an ex-
plosion in said chamber for actuating said
heads.

2. A bomb comprising a plurality of rows
of projectile chambers, said rows being ar-
ranged in a plane radiating from a given
axis, means for discharging projectiles from
said chambers, a member for each row of
chambers and carrying firing pins for the
chambers of the respective row, movable 100
heads, normally inclined links operatively
connecting said heads to said members, and
means for actuating said heads embodying
an explosive chamber, and a plug normally
105 closing such explosive chamber and dis-
placeable by an explosion therein to actuate
said heads.

In testimony whereof, I have hereunto
set my hand in presence of two subscribing
witnesses.

RALPH JIARDINA.
